UNITED STATES PATENT OFFICE.

McION JAMES DOUGLAS CARTER, OF HACKNEY, LONDON, ENGLAND,
ASSIGNOR TO A. B. DICK COMPANY, OF CHICAGO, ILLINOIS, A
CORPORATION OF ILLINOIS.

DUPLICATING APPARATUS.

No. 828,920.

Specification of Letters Patent.

Patented June 19, 1906.

Application filed June 27, 1904. Serial No. 214,873.

To all whom it may concern:

Be it known that I, McION JAMES DOUGLAS CARTER, a subject of the King of Great Britain, residing at 2 Wayland avenue, Hackney, 5 London, England, have invented a certain new and useful Improvement in Duplicating Apparatus, of which the following is a specification.

The present invention relates generally to 10 duplicating apparatus, and particularly to an interleaving device for use in connection therewith.

The object of the invention is to provide 15 means for preventing the smearing of prints as the same are fed successively from an apparatus of the character referred to.

In carrying out the invention in an approved form I employ a number of sheets of absorbent material suitably supported in 20 juxtaposition to a printing or duplicating apparatus and overlying that portion of such apparatus which receives the printed sheets therefrom. In connection with such absorbent sheets I employ means for releasing the same successively and at intervals corresponding to the delivery of printed sheets 25 from the duplicating apparatus, the whole being so arranged as that an absorbent sheet shall be delivered to the receiving-tray or 30 other device of the mechanism so as to fall on and protect the printed face of each printed sheet.

In a preferred form of the invention the mechanism for releasing the absorbent sheets 35 comprises a movable support, which may advantageously be actuated by the movement of the printing-press or duplicating apparatus, this support taking the form of a frame having inwardly-extending pins, on which 40 the pile of absorbent sheets is laid. The edges of the sheets are provided with notches of such depth as to permit these pins to pass therethrough when the pins and notches are brought into registry. These notches, however, do not correspond in all of the absorbent sheets, but only in the alternate absorbent sheets, so that when reciprocating movement is imparted to the frame and its attached and inwardly-extending pins the 45 movement of such frame causes the pins carried thereby to register with the notches of but one absorbent sheet at a time, thereby

releasing that sheet and permitting it to fall upon the printed sheet which has previously been fed from the duplicating or printing apparatus.

In the drawings showing a preferred form of the invention, Figure 1 is a side elevation illustrating the interleaving device applied to a stencil duplicating-machine of the type known as the "rotary neostyle." Fig. 2 is a plan view of the interleaving-sheet attachment. Fig. 3 is a central vertical section of said attachment. Fig. 4 is an enlarged detail view illustrating the coaction of the pins carried by the interleaving-sheet support and the sheets themselves. Fig. 5 is an enlarged detail view illustrating the relation of the printed sheets and the absorbent sheets with which said printed sheets are interleaved. Fig. 6 is a side elevation illustrating a modification, and Fig. 7 is a detail view illustrating the sheet-releasing device of the apparatus shown in Fig. 6.

Referring to the drawings, in which similar letters denote corresponding parts, A designates a duplicating apparatus, which may be of any desired construction. Since it does not form part of the present invention, the construction illustrated need not be described in detail beyond referring to the side members *a* of the frame, the pinion *a'* on the shaft of the duplicating-machine, and the pinion *a''*, which receives motion from said pinion *a'*. The drum of the duplicating-machine may be rotated in any suitable manner—as, for instance, by the crank and handle *a''*—and movement thereby imparted to the pinions *a'* and *a''*.

B designates the forward guide-plate, here shown as having angular rearward projections *b* and a central vertical projection *b'*. Said guide-plate is supported by ears *b''*, secured to the side members *a* of the frame of the duplicating-machine. C designates the rear paper-guide, here shown as having angular forwardly-extending projections *c* and central projection *c'*. As shown, the paper-guide C instead of being vertical (as in the case of the paper-guide B) is inclined in order to permit easy introduction of the pile of sheets. Said rear paper-guide C is mounted at each end upon the brackets *c''*, carried by the base D. If desired, I may also provide

said base with upwardly-extending arms *d* for the purpose of guiding the reciprocating absorbent-sheet support now to be described.

The support for the pile of absorbent leaves is here shown as comprising a rectangular frame having the side members *E E*, connected by the end members *e e'*. The side members *E* near their forward ends are provided with studs *e²*, which operate in slots *e³*, formed in the upper ends of levers *F*, pivoted at *f* to the ears *f'*, secured to the base *D*. One of said levers *F* is provided with an angular extension *f²*, said extension, with the lever *F*, forming a bell-crank, and the extremity of said extension *f²* being pivoted at *f³* to a vertically-reciprocating bar *f⁴*, the upper end whereof is pivoted at *f⁵* to the face of the pinion *a²*. As will be seen, the rotation of said pinion imparts vertical reciprocation to the bar *f⁴*, thereby operating said bell-crank lever and imparting a horizontally-oscillating movement to the supporting-frame *E*.

The rear paper-guide *C* is provided with offset lips *c¹*, forming a seat for the rearward end of the frame *E* between said lips and the upwardly-extending members of said guide. As will be seen, therefore, said frame is supported in a horizontal plane at its forward end by the levers *F* and at its rearward end by said rear paper-guide and the brackets *c²*, whereby said guide is supported.

G designate pins carried by and projecting inwardly from the side members *E* of the reciprocating frame. On these pins (see Fig. 4) the absorbent sheets *H* are supported. said absorbent sheets *H* are provided with notches *h h'* at each side edge, the notches *h h* being nearer to the forward end of the sheet than the notches *h' h'* are to the rearward end of the sheet. As a result, although a plurality of the sheets may be notched at a time, they may before introduction into the machine be alternately reversed, so that only the notches of alternate sheets shall be in register, as illustrated in Fig. 4.

The pile of sheets notched as herein described is in operation arranged upon the pins *G* of the reciprocating carrier and the lowermost sheet released when said carrier has been moved a sufficient distance to bring the pins *G* into registry with the notches in that sheet. The release of the next sheet from the bottom is precluded, however, since its notches are not in registry with those of the lowermost sheet. To release that sheet, therefore, a return movement of the carriage is necessary, so as to bring the pins *G* into registry with the differently-placed notches in that sheet.

In the mechanism illustrated in the drawings the sheets to be printed upon are fed successively to the neostyle and the drum thereof rotated, this movement causing a reciprocating movement of the absorbent-sheet-supporting carriage corresponding with

the movement of the drum. As the sheets are printed upon by the stencil on the periphery of the drum, they are fed between such drum and the impression-roller directly underlying the same into the paper-tray *I*. As the printed sheet comes to a rest in such tray, the pins *G* are moved to a point where they register with the notches in the lowermost sheet of the pile of absorbent sheets, whereby such lowermost sheet is released and permitted to fall directly upon the upturned face of the printed sheet, and this operation may be continued indefinitely, the result being that between each two printed sheets has been interposed one of the absorbent sheets released in the manner herein stated.

It is not essential that a horizontally-reciprocating carriage be employed, as the invention may to equal advantage be embodied in a construction wherein the pile of absorbent sheets may be differently arranged—as, for instance, at an angle relatively to the horizontal. Such a construction is illustrated in Figs. 6 and 7, wherein the sheet pile may be arranged on the under side of an oblique carrier *J*. A releasing device *L* may be employed to successively release the absorbent sheets, the same having angular arms *l*, provided at their ends with studs or sheaves *l'*, which as the device is moved relatively to the pile register successively with notches formed in the edges of the absorbent sheets. Where such a releasing device is employed, it may be actuated in any suitable manner—as, for instance, by means of a pin *P*, carried by the pinion *P* of the duplicating apparatus, such pin coacting with a slot *l⁴*, formed in an arm *l*, to the end of which said releasing device may be secured. With this construction, as with that above described, an absorbent sheet is released as a printed sheet is fed into the paper-tray, so that the result of the duplicating operation shall be a pile of printed sheets interleaved with absorbent sheets.

Having now described my invention, what I claim as new therein, and desire to secure by Letters Patent, is as follows:

1. In duplicating apparatus, the combination with devices for printing and feeding sheets successively, of a plurality of movable supporting-fingers adapted to wholly support a pile of disconnected interleaving sheets having notches at their edges corresponding with said fingers, the notches of alternate sheets being in register, and means controlled by said printing and feeding devices for reciprocating said fingers to release said interleaving sheets successively and permit them to fall bodily by gravity, substantially as set forth.
2. In duplicating apparatus, the combination with devices for printing and feeding sheets successively, of a plurality of movable supporting-fingers adapted to wholly support

- a pile of disconnected interleaving sheets having notches at their edges corresponding with said fingers, the notches of alternate sheets being in register, means controlled by said printing and feeding devices for reciprocating said fingers to release said interleaving sheets successively and permit them to fall bodily by gravity, and means coacting with said sheet pile to prevent movement thereof when said fingers are reciprocated, substantially as set forth.
3. In duplicating apparatus, the combination with devices for printing and feeding sheets successively, of a horizontally-disposed rectangular frame mounted for horizontal movement, inwardly-extending projections on said frame adapted to support a pile of disconnected interleaving sheets having notches to correspond therewith, the notches of alternate sheets only being in register, and means operated by said printing and feeding devices for reciprocating said frame horizontally to release said interleaving sheets successively and permit them to fall bodily by gravity, substantially as set forth.
4. In duplicating apparatus, the combination with devices for printing and feeding sheets successively, of a horizontally-disposed rectangular frame mounted for horizontal movement, inwardly-extending projections on said frame adapted to support a pile of disconnected interleaving sheets having notches to correspond therewith, the notches of alternate sheets only being in register, means operated by said printing and feeding devices for reciprocating said frame horizontally to release said interleaving sheets successively and permit them to fall bodily by gravity, and means coacting with said sheet pile to prevent movement thereof when said fingers are reciprocated, substantially as set forth.
5. In duplicating apparatus, the combination with devices for printing and feeding sheets successively, of a plurality of fingers mounted for movement adapted to wholly support a pile of disconnected interleaving sheets, each of said sheets having a plurality of notches at each of its sides, the notches of alternate sheets only being in register, and means controlled by said printing and feeding devices, for reciprocating said fingers to release said sheets successively and permit them to fall by gravity, substantially as set forth.
6. In duplicating apparatus, the combination with devices for printing and feeding sheets successively, of a plurality of movable supporting-fingers adapted to support a pile of disconnected interleaving sheets having notches at their opposite edges corresponding with said fingers, the notches of alternate sheets only being in register, and means controlled by said printing and feeding devices for reciprocating said fingers to release said interleaving sheets successively and permit them to fall bodily by gravity, substantially as set forth.
7. In duplicating apparatus, the combination with devices for printing and feeding sheets successively, of a pile of disconnected interleaving sheets, each of said sheets having a notch on each of the lateral edges thereof and said notches being so disposed that the notches of alternate sheets only are in register, and means co-operating with said pile of sheets for supporting the same, said means coacting with said notches to release the sheets of the pile successively, substantially as set forth.
8. In duplicating apparatus, the combination with devices for printing and feeding sheets successively, of a pile of disconnected interleaving sheets, each having a plurality of notches at each of the opposite sides thereof so disposed that the notches of alternate sheets only are in register, and means co-operating with said pile of sheets for supporting the same, said means coacting with said notches to release the sheets of the pile successively, substantially as set forth.

This specification signed and witnessed this 16th day of June, 1904.
